UNITED STATES PATENT OFFICE.

OLE OLSON, OF CANBY, MINNESOTA.

FENCE-POST PULLER.

1,261,600.

Specification of Letters Patent. Patented Apr. 2, 1918.

Application filed January 2, 1915. Serial No. 232.

To all whom it may concern:

Be it known that I, OLE OLSON, a citizen of the United States, residing at Canby, in the county of Yellow Medicine and State 5 of Minnesota, have invented certain new and useful Improvements in Fence-Post Pullers; and I do hereby declare the following to be a full, clear, and exact description of the invention, such as will enable others skilled 10 in the art to which it appertains to make and use the same.

This invention relates to fence post pullers, and one of the principal objects of the invention is to provide a simple device 15 which will operate quickly for pulling posts of different diameters, and in which a lever is used provided with a chain which surrounds the post and in which the lever during the upward movement of the outer end 20 or handle will take a new bite or hold on the post automatically when the chain has been adjusted properly around the post.

Another object of the invention is to provide a fence post puller of strong, durable 25 construction which can be taken apart and packed in a small compass to occupy but little room when not required for use.

The foregoing and other objects may be attained by means of the construction illustrated in the accompanying drawing, in 30 which—

Figure 1 is a top plan view of a fence post puller made in accordance with this invention and shown connected to a post, the 35 latter being shown in section,

Fig. 2 is a sectional view taken on the line 2—2 of Fig. 1 looking in the direction indicated by the arrow, and

Fig. 3 is a side elevation of the fence post 40 puller, showing the post partially pulled from the ground and the handle of the lever broken away.

Referring to the drawing, the numeral 1 designates a standard secured to a base 2 45 and at its upper end being screw threaded as at 3. Removably secured to the screw threaded portion of the standard 1 is a U-shaped bearing member 4 comprising two spaced members, and between said members is a lever 5 pivoted upon a bolt 6 extending through the spaced members and through the lever. The lever 5 is provided with an enlarged portion 7 at the pivotal point of the same, and at the projecting 50 ends, said lever is provided with an aperture 8. A chain 9 extends through the

aperture 8 and around a post 10, said chain being adjustable around the post by means of a grab hook 9^a. The lever extends some distance in rear of the standard 1 and is 60 provided with a suitable handle 12.

The manner of operating the fence post puller may be briefly described as follows:

One end of the chain 9 is passed through the opening 8 from that side of the lever 5 to which the key 11 is secured, after which the key is engaged with the link nearest such side of the lever to secure the chain to the lever with one or more links of the chain on the opposite side of the lever. If 70 the posts to be pulled are of the maximum diameter or thickness, one link only is positioned on the opposite side of the lever 5, and after the chain 9 has been passed about one of the posts the hook 9^a is engaged with 75 this link. If the posts to be pulled are of a smaller diameter or of less thickness, the chain 9 is secured to the lever 5 to position two or more links on the opposite side of the lever 5, and the hook 9^a is engaged with the 80 link nearest such side of the post after the chain 9 has been passed about the post. The number of links positioned upon the opposite side of the lever 5 depends upon the diameter or thickness of the post to be 85 pulled. It will thus be seen that the chain 9 may be so secured to the lever 5 as to permit it to be readily and quickly connected about posts of different diameters or thicknesses and as readily and quickly disconnected from the posts. Inasmuch as it is 90 only necessary to engage the hook 9^a with that link of the chain adjacent one side of the lever 5, the chain will not have to be adjusted with relation to the lever after it 95 has been passed about the post to cause it to snugly engage the post. It should be apparent that the chain may be so connected to the lever as to permit it to fit about posts of a certain diameter or thickness by merely 100 engaging the hook 9^a with a certain link located on and adjacent to a certain side of the lever. Upon a downward movement of the handle 12 the post will be pulled tightly from the ground and as the handle 12 is 105 raised, the chain will drop upon the post and take a new bite, so that when the lever is depressed at the handle end 12 a second time the post will be pulled out from the ground and loosened so that one or two more 110 bites will remove the post from the ground.

When it is desired to pack the fence post

puller for shipping or when not required for use, the standard 1 may be removed from the bearing member 4 and it may then be packed in a small compass.

5 Various changes may be made in the details of construction without departing from the spirit and scope of the invention as defined in the claim.

What is claimed is:—

- 10 A fence post puller comprising a base, a standard mounted on the base, a lever pivoted between its ends to the standard and provided at one end with a rounded post engaging nose and having a transverse opening adjacent said nose, a key secured to one side of the lever and extending across

said opening, a chain having one end thereof of passing through the opening to position one or more links thereof on the opposite side of the lever, the link located adjacent 20 the first side of the lever being engaged by said key to secure the chain against accidental displacement, and a hook carried by the other end of the chain for engagement with that link adjacent said opposite side 25 of the lever.

In testimony whereof I affix my signature in presence of two witnesses.

OLE OLSON.
